UNITED STATES PATENT OFFICE.

HERBERT FROOD, OF BUXTON, ENGLAND.

BRAKE.

1,136,665.

Specification of Letters Patent. Patented Apr. 20, 1915.

Application filed July 25, 1913. Serial No. 781,067.

To all whom it may concern:

Be it known that I, HERBERT FROOD, a subject of the King of Great Britain and Ireland, and a resident of Buxton, in the county of Derby, England, have invented certain new and useful Improvements in Brakes, of which the following is a specification.

This invention relates to improvements in and in connection with brakes the wearing surfaces or elements of which are composed of textile or like or other non-metallic material. Such a wearing surface or element may conveniently be of the nature described in the specification to my prior British Letters Patent No. 4627 of 1909.

Brake bands or blocks of the character and substance above referred to are commonly mounted upon shoes or supports which may be metallic or non-metallic. In either case no provision has been made for immediately conducting away or dissipating the heat set up in the band or block as a consequence of the application of the brake, with the result that the shoe, support, post, or the like bearing the band or the block, has become so hot that the braking surface has been damaged by it, and in some cases, where wood has been used as a backing for the brake, the wood has been set on fire.

In carrying this invention into effect the brake band or block is mounted upon or combined with a backing or support which is of such a nature and conformation as to efficiently and readily conduct and radiate or dissipate the heat conveyed to it by the brake band or block. Such backing or support may itself form the main support for the brake block or band, but it is preferably placed between such band or the like and the post or equivalent member by which the band is carried. If the heat dissipating backing is integral with the post or the like, the necessary formation will be given to the post at or near that surface to which the brake band or block is applied.

The heat dissipating backing or like part of a post or other support is of a construction and disposition which will permit and induce the free circulation of atmospheric air through and around and about it to rapidly carry off the heat imparted to it.

The accompanying drawings illustrate various forms of heat dissipating devices com-

bined with various brake blocks and supports therefor according to this invention.

Figure 1 illustrates in side elevation a post brake for colliery winding gear having a heat dissipating backing for the brake block. Fig. 2 illustrates in front view the heat dissipating backing employed in the brake of Fig. 1. Fig. 3 illustrates in a similar view to Fig. 1 a like brake furnished with a modification of the heat dissipating device of Figs. 1 and 2. Fig. 4 is a face view of the post of Fig. 3, the brake block being removed from the post to permit the modified form of heat dissipating device to be seen. Figs. 5, 6 and 7 illustrate further modifications as applied to a post brake. Fig. 8 shows still further modifications in a post brake. Figs. 9 and 10 illustrate a form in which the heat dissipating device or part of it is integral with the support for the brake block. Fig. 9 shows the various parts in side elevation assembled together; Fig. 10 shows in like elevation the various parts separated from each other.

Similar letters of reference indicate similar or equivalent parts where they occur in the different figures.

Referring first to Figs. 1 and 2 A indicates the usual support which supports the brake block B. This brake block is of the non-metallic character or nature hereinbefore described. Between the support A and the block B is interposed a strip C of open meshed woven thick wire fabric. The edges and ends of this strip are exposed to the air, so that the channels or passages formed through and along the fabric by the meshing and intersections of its component wires are open to the air. In place of the strip of woven wire fabric of Figs. 1 and 2, lengths of old wire rope may be employed. Such an arrangement is convenient and economical for use in a colliery where such pieces of old rope are generally available. Figs. 3 and 4 show several lengths of wire rope C laid in a recess formed in that face of the support A to which the brake block B is applied. The parallel disposition of the various lengths of rope in the manner shown produces longitudinal air spaces or channels between the various lengths, and the convolutions of the strands of the different lengths provide transverse air channels leading into the longitudinal ones. The edges of the recess in the support are perforated as at D

so as to give atmospheric communication to the various air channels in and between the ropes.

In the modification of Figs. 5, 6 and 7 a metal plate C having transverse ribs or fins projecting from one face is interposed between the block B and the support A. When the plate is in place its edges are open to the air. The plate may be closely perforated 10 into the spaces between the transverse ribs as shown at E in Fig. 7. In Figs. 5 and 6 the plate C is shown formed for the application of the brake block to its smooth face and with its ribbed face for application to 15 the support A. This arrangement may be reversed, that is the ribbed face may bear the brake block and the smooth face be applied to the support. With this reversed arrangement the perforations E are not necessary. In Figs. 5, 6 and 7 the grooves produced by the ribs are shown as only extending transversely across the plate C. If desired, however, other grooves, for example longitudinal ones, may be formed on the face 20 of the plate instead of or in addition to the transverse grooves.

The brake shown in Fig. 8 has a transversely corrugated strip of metal C disposed between the support and the block B.

30 In the form of brake and heat dissipating device shown in Figs. 9 and 10 the face of the metallic shoe or support A is transversely grooved as illustrated at C¹. On this grooved face is laid a thin sheet metal plate C² which may be closely perforated. 35 The block B is laid on the plate C².

A plate such as C² may be laid on the

face of the corrugated strip of metal C of Fig. 8 and be of sufficient stiffness to prevent the substance of the block B being depressed into the valleys of the corrugated strip.

What I claim is:

1. In a mechanical brake, a textile brake block, a support therefor, and a metallic heat conducting backing interposed between the two, said backing being formed with air-passages therein to effectively radiate the heat taken up by the backing from said block, substantially as described.

2. In a mechanical brake, a textile brake block, a support therefor, and a metallic backing interposed between said block and support having a plurality of heat radiating surfaces and air-passages for conducting heat away from the block and support.

3. In combination a textile brake block, a support therefor, having a ribbed metallic heat radiating surface interposed between the block and the main body of said support, substantially as set forth.

4. In combination a textile brake block, a grooved metallic shoe therefor and a thin metal plate interposed between the grooved metallic shoe and the block; substantially as set forth.

In witness whereof I have hereunto set my hand in the presence of two subscribing witnesses.

HERBERT FROOD.
